CLAIM

We claim, the ornamental design for furniture for a television receiver, as shown and described.

DESCRIPTION

FIG. 1 is a front perspective view of furniture for a television receiver showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines in FIGS. 1-7 illustrating portions of the furniture for a television receiver form no part of the claimed design.

1 Claim, 6 Drawing Sheets
